UNITED STATES PATENT OFFICE.

ALFRED E. BUHRKE, OF RIVER FOREST, ILLINOIS, ASSIGNEE TO R. H. BUHRKE CO., OF CHICAGO, ILLINOIS, A CORPORATION OF ILLINOIS.

GOLF-CLUB CONSTRUCTION.

Application filed December 9, 1927. Serial No. 238,746.

This invention relates to golf club construction and has special reference to a locking means for securing inserts in the striking face of the head of a golf club.

More particularly, this invention relates to a locking means for securing an insert or a group of inserts in the striking face of a golf club in such a manner as will obviate the difficulties due to the shrinking or expanding of the body portion of the club head which interferes with the efficiency of the golf club to secure the proper impact upon the ball when struck to insure long distance flight and other desirable qualities sought in a golf club.

Ordinarily inserts have been threaded or threaded and glued within the golf club head whereupon any expanding of the golf club head will permit the insert to become loosened which will interfere materially with the flight of the ball. Further, such expansion of the golf club head will leave play around the insert and will cause a splitting of the insert, particularly across the portion where the threads commence due to the impact received when striking the ball. Again glue is subject to climatic conditions and will not perform the desired functions unless these conditions are desirable.

In the present construction, it is desirable to use inserts which are smooth and at least one of which is of metal, they being so constructed and arranged as to minimize the hazards engendered by the alterable qualities of the material of the head. Moreover, these inserts are so held in position within the golf club head as to prevent the same from moving forwardly or rearwardly or becoming loosened in any manner. This is accomplished by means of locking the securing means within the golf club head by a secondary means such as a sole plate, it being further desirable that the sole plate and the insert have no interconnecting means.

One of the objects of this invention is to provide an improved means for positively connecting the insert or inserts with the main body of the club head so as to prevent the latter from moving forwardly or rearwardly or becoming displaced by the shrinking or expanding of the club head proper.

Another object of this invention is to provide means for locking the securing means of the insert in the club head whereby the inserts will remain tightly seated therein.

A further object of this invention is to provide a plurality of inserts for the head of a golf club whereby one of the inserts, being securely held in the body portion of the club head, holds the remaining inserts in a positive relation therewith.

A still further object of this invention is to provide a golf club construction which is durable, which may be readily assembled and which is pleasing in appearance.

Further objects and advantages of this invention will be apparent from the description and drawings forming a part of this specification to which latter reference may now be had for a more complete understanding of the characteristic features of this invention, in which drawings:

Figure 1 is a front elevational view of a golf club head in which one form of this invention is embodied;

Fig. 2 is a view similar to Fig. 1 showing a portion thereof in section;

Fig. 3 is a central sectional view taken on the line 3—3 of Fig. 1;

Fig. 4 is a front elevational view of a golf club head in which another form of this invention is embodied;

Fig. 5 is a view similar to Fig. 4 showing a portion thereof in section; and

Fig. 6 is a central sectional view taken on the line 6—6 of Fig. 5.

Referring now to the drawings and more particularly to Figs. 1, 2 and 3 thereof, a golf club head 10 is shown which is of wood or other suitable material having a face plate 11 inlaid in the striking face 12 thereof. The face plate 11 is preferably of fiber, hard rubber or other suitably tough material for the reason that the wearing properties thereof are more desirable than that of wood and for the further reason that the grain of the wood forming the golf club head ordinarily extends parallel with the striking face 12.

A substantially large impact insert 13 is embedded in the lower portion of the golf club head and is disposed substantially centrally of the width thereof. A counterbored socket 14 is provided at the lower end of the golf club to receive the impact insert in snug engagement therewith, the larger outer portion of the counterbored socket extending a substantial distance through the face plate 11, the smaller or inner portion of the socket extending through the remaining portion of

the face plate and into the body portion of the club head. The socket has a preferably semi-circular contour and the impact insert 13 is shaped so as to conform to the socket, 5 the lower edge of the latter being substantially flat to extend flush with the lower surface of the club head. The outer end of the head 15 of the impact insert has a substantially flat surface and is preferably flush with 10 the striking face 12 and the face plate 11, the latter elements being inclined rearwardly from the bottom of the golf club as is usual in golf club construction.

The impact insert 13 is held in a positive 15 fixed relation with the golf club head by means of a screw 16 extending from the flat lower side of the latter through the shank or smaller portion of the insert to be secured to the body portion of the club head. The screw 20 16 is further held in position by means of a sole plate 17 suitably secured as by means of screws 18 to the bottom surface of the club head. The sole plate prevents the displacement of the screw 16 and the screw 16 in turn, 25 by reason of its being prevented from becoming loosened, holds the impact insert 13 in a fixed relation with the club head. It is to be understood that the securing means 16 may be a pin instead of a screw and that such a 30 pin will as effectively secure the relative parts as will the member shown.

The head 15 of the impact insert 13 serves further to hold a plurality of auxiliary impact inserts 19 in position in the club head. 35 These inserts 19 are embedded in the body portion of the club head and extend through the face plate 11, the outer end thereof being flush with the striking surface of the face plate 17. The inserts are positioned adjacent 40 the periphery of the impact insert 13, the flanged portion of the head 15 overlapping a comparatively small portion of the inserts and being countersunk therein. In the drawing three such auxiliary inserts 19 have been 45 provided, although any number thereof may be provided which may be of any size in keeping with the appearance of the golf club head and the utility thereof.

It is preferable that the insert 13 be of 50 metal, for the reason that it affords an absolutely rigid or solid driving surface which, however, is not inert. The material of the inserts 19 is preferably of ivory or some other hard composition which may be distinctively colored and arranged to produce a striking and ornamental design.

It is seen from the foregoing that the auxiliary inserts 19 are securely anchored in the 60 golf club head by means of the head 15 of the insert 13, and that the latter, in turn, is rigidly fixed in a socket provided in the lower end of the golf club head by means of a screw 16, the securing means being locked in a position such that it cannot become loosened by 65 means of a sole plate 17. By thus locking the

inserts in position in the golf club head, it is found unnecessary to provide the inserts with screw threads, glue, or the like, which latter means are undesirable due to the shrinking or expanding of the material of the 70 golf club head which cracks the same across the threaded portion upon shrinking or so loosens the insert that a solid blow cannot be transmitted to the golf ball. Again, it is found very desirable to use a metal insert 13 75 for the reason that it affords the requisite resistance and solidity which enable the user to continue the stroke after the force of impact has been transmitted to the ball which in the language of the players is called the "follow 80 through."

Referring now to Figs. 4, 5 and 6 of the drawings, an impact insert of a modified form is shown, although it is substantially the same as that of the previously described insert. In 85 this instance, the insert may be made of a cylindrical shape having a head portion 20 and a reduced body portion 21. A counter-bored socket 22 is provided in the face plate 23 of the club head and extends a substantial 90 distance into the body portion thereof. The insert is preferably of metal, the outer surface of the head portion 20 being flush with the striking surface of the face plate 23, these latter members being inclined rearwardly 95 from the lower edge of the head as is usual in golf club construction. The insert is held in position by means of a screw 24 extending from the bottom surface of the club 25 to threadedly engage the insert. A sole plate 26 100 is provided on the bottom surface of the golf club head and is secured thereto by means of screws 27, the sole plate thus locking the screw 24 in a position such that it cannot become loosened. A plurality of auxiliary inserts 28 are disposed adjacent the periphery of the reduced portion 21 of the centrally disposed impact insert, the head portion 20 thereof overlapping and seating in cut-away portions 29 formed at the outer extremity of the 110 auxiliary inserts.

As in the perviously described embodiment, these auxiliary inserts 29 may be formed of ivory or a composition such that they may be easily colored whereby a striking ornamental 115 effect may be obtained. These inserts are further disposed so that the vibrations set up in the club may be distributed throughout the club and thereby introduce a harmonious vibration of the head as a whole upon the force 120 of the impact with the golf ball. Further, inasmuch as the securing means, such as the screws 16 and 24, are locked in position as by means of the plates 17 and 26 respectively, it is to be understood that a pin or other like securing member may be used as effectively as a 125 screw.

While several embodiments of this invention have been herein shown and described, it is to be understood that many modifications 130

thereof may be apparent to one skilled in the art without departing from the spirit and scope of this invention and it is desired that the same shall be limited by the scope of the 5 appended claims and the showing of the prior art.

I claim:

1. The combination with the head of a golf club, of an insert set flush with the striking 10 face of said head, means extending from the bottom surface of said head to secure said insert, and means secured to the bottom surface of said head for locking said securing means.

15 2. The combination with the head of a golf club, of an insert comprising a body portion and a head portion, the outer surface of said head portion being set flush with the striking face of said head, means extending from the 20 bottom surface of said head to secure said insert, and means secured to the bottom surface of said head for locking said securing means.

25 3. The combination with the head of a golf club and a face plate therefor, of an insert set flush with the striking surface of said face plate and extending into said head, means in said head for securing said insert, and means secured to said head for locking 30 said securing means, said insert fixedly positioning said face plate in said head.

35 4. The combination with the head of a golf club, of an insert set flush with the striking face of said head, means extending from the bottom surface of said head to secure said insert, and a sole plate secured to the bottom surface of said head for locking said securing means.

40 5. The combination with the head of a golf club and a face plate therefor, of an insert set flush with said face plate, a plurality of auxiliary inserts mounted in said head, and means for securing said first mentioned insert, said first mentioned insert fixedly positioning said auxiliary inserts and said face plate in said head.

45 6. The combination with the head of a golf club and a face plate therefor, of an insert comprising a smooth body portion and an enlarged head portion, said head portion being seated in said face plate and having its outer surface flush therewith, and means in said club head for engagement with said body portion for securing said insert and said face plate in a fixed relation with said club head.

50 7. The combination with the head of a golf club and a face plate therefor, of an insert comprising a body portion and a head portion, said head portion being seated in said face plate and having its outer surface flush therewith, means extending from the bottom surface of said club head for engagement with said body portion for securing said insert and said face plate in a fixed relation

with said club head, and a sole plate for attachment to the bottom of said club head for locking said securing means.

8. The combination with the head of a golf club, of an insert comprising a body portion and a head portion, a plurality of auxiliary inserts adjacent said first mentioned insert, said head portion being set flush with the striking face of said club head and engaging said auxiliary inserts to hold the latter in a fixed relation with said club head, means for securing said first mentioned insert, and a member for locking said securing means.

9. The combination with the head of a golf club, of an insert comprising a body portion and a head portion, a plurality of auxiliary inserts adjacent said first mentioned insert having recesses formed in a portion thereof, said head portion engaging said recesses for holding said auxiliary inserts in a fixed relation with said club head, means for securing said first mentioned insert, and a member for locking said securing means.

10. The combination with the head of a golf club, of an insert comprising a body portion and a head portion, a plurality of auxiliary inserts adjacent said first mentioned inserts and set flush with the striking face of said club head, said auxiliary inserts having cut-away portions in the outer surfaces thereof for engaging said head portion, said head portion being set flush with said striking face, means extending from the bottom surface of said club head for securing said first mentioned insert, and a sole plate for attachment with the bottom of said club head for locking said securing means.

11. The combination with the head of a golf club, of a metal insert set flush with the striking face of said head, a screw member extending from the bottom of said head for engaging and holding said insert in a fixed relation with said club head, and a sole plate secured to the bottom of said club head for locking said screw member.

12. The combination with the head of a golf club and a face plate therefor, of a metal insert comprising a body portion and a head portion, said head portion being seated in said face plate and having the outer surface thereof set flush with the outer surface of said face plate, a screw member extending from the bottom of said club head and engaging said body portion, and a sole plate attached to the bottom of said club head for locking said screw member.

13. The combination with the head of a golf club and a face plate therefor, of a metal insert comprising a body portion and a head portion, said head portion being seated in said face plate and having the outer surface thereof set flush with the outer surface of said face plate, a plurality of auxiliary insert members disposed adjacent said first mentioned insert member and set flush with said

face plate, said auxiliary inserts being recessed at their outer ends to snugly engage the periphery of said head portion, said first mentioned insert holding said auxiliary inserts and said face plate in a fixed relation with said club head, a screw member extending from the bottom surface of said club head to engage said body portion, and a sole plate secured to said bottom surface of said club head for locking said screw member.

14. The combination with the head of a

golf club, of an insert set flush with the striking face of said head, a plurality of auxiliary inserts grouped adjacent said first mentioned insert, and means extending from the lower 15 surface of said club head for securing a plurality of said inserts in a fixed relation with said club head, and means on the bottom of said head for locking said securing means.

In witness whereof, I have hereunto subscribed my name.

ALFRED E. BUHRKE.
